UNITED STATES PATENT OFFICE

2,387,484

REFRIGERATION UNIT

Charles H. Walbert, Oklahoma City, Okla.

Application October 13, 1943, Serial No. 506,105

17 Claims. (Cl. 62—55)

This invention relates generally to the class of refrigeration and is directed particularly to an improved icing unit designed to be installed in a standard ice box or refrigerator for controlling the humidity as well as the air temperature thereof.

A principal object of the present invention is to provide a refrigeration or icing unit for iced refrigerators which is constructed in a novel manner whereby there is provided a top ice compartment and a rear or back ice compartment with novel means for effecting the controlled circulation of refrigerated air whereby the maximum of refrigeration efficiency is obtained.

Another object of the invention is to provide an air and humidity conditioning iced refrigeration unit having an upper or top ice compartment which is provided with a novel double floor construction and door means connected therewith whereby the ice supporting bottom or floor of the ice drawer compartment can be drawn out as a drawer to facilitate the introduction of ice or its removal and to prevent the dripping of water from the compartment onto the floor and down the front of the refrigerator.

Still another object of the invention is to provide a novel icing unit having in addition to an upper or top ice compartment, a shallow vertically disposed ice chamber communicating with the bottom of the top compartment, at the rear of the latter, and extending downwardly through the back of the refrigerator, with ventilating openings leading from the upper and lower portions of the vertical ice compartment through which the refrigerated air may circulate into and out of the refrigerator food chamber.

Still another object of the invention is to provide in association with a unit of the above described character, means for introducing into the upper part of the upper ice compartment, warm air taken from the food chamber, and for circulating air from the food chamber around the upper ice compartment, and returning it into the ice compartment after passing it over the outer sides of the refrigerated walls of such compartment.

A further object of the invention is to provide in a refrigeration unit of the character stated, a novel means for humidifying the air circulating through the food compartment, which includes the construction of the floor of the upper ice compartment with a downward and rearward inclination whereby water from the melted ice will flow to the rear of the unit and down over the inner

surfaces of the vertical ice compartment into a reservoir in the bottom of the refrigerator.

Another object of the invention is to provide in association with the structure above described, a lower or bottom cold water chamber or reservoir, of relatively shallow construction, which forms the bottom wall for the food compartment, upon which may be placed articles of food, more particularly meats and other items which must be kept very cold to prevent spoilage.

It is also an object of the present invention to provide in association with the cold water reservoir, a novel means for filtering the water before it enters the reservoir whereby to remove therefrom such bacteria as are responsible for the development of slimes in those chambers of refrigerators where ice water must stand.

Still another object is to provide, in association with the cold water reservoir above referred to, a novel means of syphoning off the water from the reservoir when and as necessary.

The invention broadly contemplates the provision of a unit having an upper rectangular portion open at its top and having back and side walls, a bottom wall or floor of double construction whereby one portion may be drawn forwardly with respect to the other so as to extend such one portion through the front icing door of the refrigerator, and a front wall connected with the front edge of the movable floor portion and comprising two hingedly connected sections which can be swung outwardly and downwardly to a horizontal position to facilitate introduction of ice. Connected with and extending downwardly from the back part of the above described upper portion of the unit is a vertical relatively shallow ice chamber which positions in the back part of the food chamber of the refrigerator. This shallow ice chamber has a bottom screened opening and it also has front screened openings at the bottom and at the top, which are directed into the food chamber. These screened openings may be covered or uncovered as desired for the purpose of controlling the circulation of refrigerated air to the food compartment. The walls of the upper chamber are constructed to maintain a slight spaced relation with the adjacent walls of the refrigerator whereby to provide air ducts around the icing chamber, the back and side walls of the icing chamber or upper portion of the unit being provided with circulation ports through which rising warmer air is permitted to enter the ice chamber.

In association with the above described structure there is provided a relatively shallow or flat

water reservoir which lies upon the bottom of the refrigerator food chamber and which communicates with a well which is open at its top and which lies under the screened bottom of the back or vertical ice chamber to receive therefrom water from the melting ice and condensate. This well has associated therewith means for filtering the water before it enters the cold water reservoir and also means for siphoning off water from the reservoir and well when necessary. Hence this cold water reservoir forms a bottom shelf for the food compartment upon which may be placed meats or other articles of food which must be kept very cold. There is also associated with the bottom shelf constituting the cold water reservoir, a chamber forming unit which is open at its front to receive special articles such as bottles of milk, and which has an opening at the back arranged to coact with a cold air discharging opening of the vertical ice cabinet or chamber whereby the cold air will enter into the special compartment and be confined therein so as to maintain bottles of milk or other products at the lowest possible temperature.

Another object of this invention is to provide a refrigeration unit designed to use all types of ice namely, block ice, crushed ice, sized ice, cube ice, flake ice, tube ice or what is termed snow ice in ice compartments without any changes in ice compartments whatsoever and by the use of the crushed, flaked, snow or other finely divided ice vegetables and fruits may be embedded in the ice to protect the vitamin content of said fruits and vegetables without effecting refrigeration in a lower food compartment of the refrigerator.

Other objects and advantages of the present invention will become apparent as the description of the same proceeds and the invention will be best understood from the consideration of the following detailed description taken in connection with the accompanying drawings with the understanding, however, that the invention is not to be confined to any strict conformity with the showing of these drawings but may be changed or modified so long as such changes or modifications mark no material departure from the salient features of the invention as expressed in the appended claims.

In the drawings:

Figure 1 is a view in front elevation of a refrigerator showing the refrigeration unit of the present invention in position therein.

Figure 2 is a view in front elevation of the unit removed from the refrigerator and having the ice drawers removed therefrom.

Figure 3 is a vertical section of the line 3—3 of Fig. 2.

Figure 4 is a top plan view of the structure of Figure 2.

Figure 5 is a transverse section through the upper part of the unit with the middle portion of the back of the unit broken away, being substantially on the line 5—5 of Figure 3 and showing portions of adjacent refrigerator walls and supporting brackets thereon.

Figure 6 is a horizontal section through the upper ice chamber of the unit as installed the section being on the line 6—6 of Figure 10.

Figure 7 is a detail section on the line 7—7 of Figure 6.

Figure 8 is a top plan of the ice drawer per se.

Figure 9 is a view in front elevation of the ice drawer one side being sectioned on the line 9—9 of Figure 10.

Figure 10 is a sectional view on the line 10—10 of Figure 8.

Figure 11 is a view in top plan of the condensation tray.

Figure 12 is a view in front elevation of the condensation tray with a portion sectioned substantially on the line 12—12 of Figure 11.

Figure 13 is a section on the line 13—13 of Figure 11.

Figure 14 illustrates the condensation tray in side elevation and in installed position.

Figure 15 is a view in top plan of the cold water receptacle.

Figure 16 is a view in side elevation of the cold water receptacle.

Figure 17 is a view in top plan of the removable milk compartment unit.

Figure 18 is a front elevation of the milk compartment.

Figure 19 is a side elevation of the unit with the top sectioned on the line 19—19 of Figure 18.

Referring now more particularly to the drawings wherein like numerals of reference indicate corresponding parts throughout several views, the unit is here illustrated as being installed in a refrigerator cabinet of the type and size customarily used in homes but it is to be understood, of course, that its use is not so restricted as the invention is capable of application to commercial installations as well as domestic ones, and it may also be used in such structures as refrigerator cars or refrigerated trucks.

The housing cabinet is generally designated C and in the form illustrated has the usual upper or top compartment T and the lower or underlying food compartment generally designated F. The door openings leading into these compartments are separated by the usual transverse bar or sill S.

The structure herein disclosed is formed in two main units which, while they are designed to be used together, they can under certain conditions, be used separately in different types of installations. Such units are designated A and B, the unit A comprising the ice receiving and air circulating unit and the unit B comprising a filter, water siphoning means and cold water reservoir.

The icing unit A comprises an upper section A' which forms the top ice chamber and a lower section A'' which forms the lower ice chamber. The upper section or top ice chamber positions within the top chamber T of the ice cabinet and comprises the side walls 10 back wall 11 and bottom wall 12. As shown the back wall 11 extends all the way down to the bottom of the lower ice chamber A'' and forms the back wall for such lower chamber and portions of the side walls 10, at the back of the unit, are extended downwardly as indicated at 10' to provide the side walls of the lower ice chamber.

The overall width of the unit is such that when the unit is installed in the refrigerator cabinet there will be provided at the sides and in the back an air circulation space 13.

At the vertical front edge of the side wall portion 10 there is provided the lateral flange 14 which engages the adjacent side wall 15 of the cabinet while the top edge of each side portion 10 has a similar lateral flange 16 which engages the adjacent side wall 15 and the top edge of the back wall 11 has the outwardly extending flange 17 which engages the back wall 18 of the cabinet.

The side wall portions 10 and the back wall 11, have a series of air inlet apertures 19, formed therethrough in a line paralleling the adjacent

edges and upon the inner side of each side wall portion and of the back wall there is formed an air duct 20, having air admission openings 21 leading into the top ice chamber, such openings being controlled by an apertured side plate 22.

The lower ice chamber A" is relatively shallow and is of a length to extend from the plane of the sill S nearly to the bottom of the food compartment. The forward part of the lower ice chamber is closed by the front wall 23 and the side walls 10 of the lower ice chamber are of slightly increasing width from the upper to the lower ends so that this lower ice chamber which in effect forms a shallow throat between the lower part of the upper ice chamber and the lower part of the food compartment, is of gradually increasing depth from the top to the bottom. This facilitates the movement of ice downwardly through the lower ice chamber, particularly when such ice is put in, in the form of broken ice, crushed ice, sized ice, cube ice, tube ice, or snow.

As is clearly shown in Figure 3 the bottom wall 12 has a slight inclination downwardly from the forward to the rear edge and at the rear edge of the bottom wall 12 there are provided apertured plates or screens 24 which, in effect, form a continuation of the bottom wall and cover the upper part of the lower ice chamber.

At the top of the front wall 23 of the lower ice chamber, there are provided the two air openings or ports 25 each of which is covered by a screen 26. Means is provided, in the form of sliding doors 27 for covering these ports when desired to prevent the flow of air therefrom. These ports open into the top part of the food compartment.

The wall 23 of the lower ice compartment is also provided at the bottom with the cold air admission ports 28, each of which is covered by a hinged door, or otherwise suitably movable, screen 29.

The bottom of the lower ice compartment or chamber is covered or closed by the apertured or screened wall 30 whereby the escape of ice from the lower part of the lower ice chamber is prevented but the cold air and water are allowed to pass through into the bottom of the food chamber.

Extending vertically through and upon the vertical center of the unit, is a cold air duct which is generally designated 31. This duct divides the lower ice chamber into two sections and the upper and lower air ports, 25 and 28 open through the front wall of the ice chamber at the two sides of this vertical air duct. This air duct opens downwardly at its lower end into the food compartment and at its upper end it is provided with laterally directed screened openings 32, through which warm air, which has risen from the food cabinet or chamber, may enter into the upper ice chamber. The air duct also serves the additional purpose of strengthening the front and back walls 11 and 23.

When the refrigeration unit is installed in the cabinet, any suitable means may be provided for maintaining the unit suspended therein so that the top flanges 16 and 17 will be in close relation to or in contact with the top wall of the top compartment 15. A desirable means of suspending the unit may be providing an angle bar 33 along the inner face of each side wall and across the back wall of the cabinet in which the upper ice compartment is located, in close proximity to the top of such cabinet as shown in Figure 5 with one flange extending inwardly so as to have engaged

thereover the adjacent side and back flanges 16 and 17 which form integral parts of the side and back walls of the upper ice compartment. With this arrangement the unit is firmly suspended in the refrigerator cabinet and air rising between the walls of the installed unit and the walls of the cabinet can pass through the apertures 19 and 21, when the slides 20 are properly positioned, into the upper part of the upper ice compartment.

When the unit is installed in the cabinet it is, of course, placed back as best seen in Figure 3, so that the front lateral flanges 14 will be set back slightly from the edge of the adjacent door opening. This allows for an air space at the front between the upper ice chamber and the front door of the refrigerator as hereinafter described.

At the forward or front edge of the bottom 12 of the upper or top ice chamber, there is secured along the inner or back face of the sill S, the apertured plate 35, Figure 7. The apertures 36 of this plate may be closed when desired, by the employment of an apertured slide 37 so that the flow of air upwardly from the food compartment may be shut off when desired.

If desired, instead of using the apertured plate 35, and forming it as a separate unit to be secured against the back of the sill S, the floor or bottom 12 of the top ice chamber may be extended and secured to the sill and such extended portion provided with air openings.

The numeral 38 generally designates a movable or slidable drawer unit. This drawer unit comprises a bottom or floor 39 which rests upon the bottom 12 and which is joined at its sides with the short upstanding side walls 40 which position against the inner walls 10. These side walls 40 are extended inwardly beyond the inner edge of the bottom 39, so that when the drawer is in position within the upper ice chamber the inner or back edges of the side walls 40 will be in abutting relation with back wall 11 but the bottom 39 of the drawer will not be extended to the point where it will cover the screens 24.

The side walls 10 of the top ice chamber have secured thereto the guides 41, in each of which the top edge of a side wall 40 of the drawer slideably engages.

Hingedly secured as at 42 to the forward edge of the bottom 39 of the drawer is a two part door 43. This door is divided transversely to form the two sections 44 and 45, which sections are hingedly joined together so that they swing or oscillate on a horizontal axis. When the door 43 is in closed position the ends of the upper section will bear against the faces of the vertical flanges 14 to close the front of the top ice chamber.

As will be readily apparent the drawer 38 is designed to be shifted forwardly or outwardly through the door opening for the top compartment T out of the cabinet and when so shifted the door 43 may be swung downwardly. The lower section 44 of the door is designed, however, to be lowered only to a horizontal position and this action is obtained through the attachment to each side of the lower door section, of a hinged bracket rod 46 which at its inner end has sliding connection with the adjacent side wall 40. There is also provided at each side of the lower door section 44, the arcuate wing plate 47 which, when the door is dropped to open position, substantially forms an extention of the adjacent side wall 40 to prevent the escape lateral-

ly of loose ice which may be lying upon the bottom of the drawer.

The drawer 38 provides a convenient means for placing ice in the ice chambers as well as for effecting the removal of ice therefrom, and it also provides a guard to prevent ice, falling out of the chamber and also for preventing drippings from falling on the floor and down the front of the refrigerator.

When the drawer is in closed position and the door is shut, it will be seen that there will be a space 48, Fig. 7, between the front of the drawer and the cabinet door by which the opening leading to the top compartment is closed. When the slide 37 is in closed position with respect to the air openings 36 in the plate 35, then this space 48 becomes a dead air space to function as insulation means but if the slide is in open position then air may circulate upwardly from the food compartment and such relatively warm rising air will pass out from the top compartment when the front door thereof is opened.

Disposed behind the sill S and directly beneath the bottom wall 12, of the top ice chamber is a condensation collector tray which is indicated generally by the numeral 49. This condensation tray comprises a bottom pan 50 and an upper or top pan 51. The bottom pan has extending along each side the upstanding flange 52, which is integral with a front upstanding flange 53 and the rearwardly directed side extensions 54. These side extensions 54, provide positioning means for the condensation tray, being designed to extend across the side walls 10' of the lower ice chamber as illustrated in Figure 14. The inner or back edge of the bottom pan is spaced slightly from the front wall 23 of the lower ice chamber, when the condensation tray is in operative position, as shown in Figure 14 and such inner or back edge of the bottom pan has a short depending lip 50' integral therewith.

The top pan 51 is supported by suitable brackets 55 in spaced relation with the bottom pan and both the bottom and top pans have air vents or openings 56 therethrough each of which is covered by a hood 57 which is supported by suitable brackets 58 in spaced relation with the underlying pan bottom.

The condensation tray is suspended for easy removal beneath the upper ice chamber in the following manner. There are secured to the front wall 23 of the lower ice chamber brackets 23' upon which rests the edge of the lip 50' as shown in Figure 14. At the front of the upper ice chamber the bottom wall has secured thereto, to extend transversely of the chamber, the hanging forwardly extending flange 12'. This flange is in spaced relation with the slide 37 which is disposed beneath the apertured plate 35 and the top edge of the front upstanding flange 53 of the condensation tray has an inturned flange 53' which engages over the forwardly extending edge of the flange 12' as shown in Figures 7 and 14 so as to hang the front part of the condensation tray in position. Removal of the condensation tray is easily effected by lifting up the rear part of the tray to raise the lip 50' from the brackets 23' and then shifting the tray forward slightly to disengage the flanges 12' and 53' whereupon the tray can be dropped and removed through the door opening of the food compartment.

The front flange 53 of the condensation tray is provided with air apertures 59 whereby air may circulate between the bottom wall 12 and the

condensation tray to pass out at the front and up through the apertures 36. The condensation tray is positioned approximately one and one-half inches below the bottom 12 of the upper or top ice chamber and functions to receive or catch any moisture forming upon and dripping from such bottom wall and prevent the same from passing downwardly into the underlying food compartment. At the same time, by reason of the openings 56 covered by the raised hoods 57, the cold air from the overlying ice chamber may pass down freely into the food compartment.

The bottom wall 12 of the upper ice chamber and the condensation pan are inclined downwardly toward the rear and thus water from melting ice and condensate collected in the condensation pan, will be rapidly carried off.

The unit B comprises a relatively flat receptacle having top and bottom walls 60 and 61 respectively and the front and side walls 62 and 63. Extending across the back of the unit is an upstanding rectangular well 64 which is open at its top and which communicates with the interior of the front part of the unit. This structure forms a cold water reservoir. The overall width and length of the cold water reservoir is such that it fits the width and depth of the bottom wall or floor of the food compartment and the open top of the well lies directly beneath but is spaced from the open screened bottom of the lower ice chamber. It will thus be seen that the lower unit receives the ice water from the overlying ice chamber and it forms a refrigerated floor for the lower part of the food compartment upon which meats or other foods, which have to be kept very cold, may be placed.

In order to facilitate the cleaning of the cold water reservoir and the more rapid transmission of cold to the top wall 60 thereof, such top wall has secured to its underside a number of metal fins 65.

Also associated with the bottom unit is a filtering unit which is generally designated 66 and which is formed preferably, though not necessarily, in two sections which fit in the top of the well.

There is also provided as a part of the lower unit B a siphon and drain valve unit which is generally designated 67.

No detailed illustration or description of the features of the lower unit B are given since these features are illustrated in and form the subject matter of copending applications Ser. Nos. 506,104 and 506,106, both filed October 13, 1943. While the well portion of the cold water reservoir forms in the combination with the refrigerating unit, a means for receiving condensate and water from the melting ice it will be readily apparent that other means may be readily provided for receiving such water and also it is contemplated to use the cold water reservoir in association with other refrigerating units as, for example, this reservoir may be used in a refrigerated car where, by suitably increasing the dimensions of the forward shallow portion of the unit, it may form a refrigerated floor for such structure.

As an auxiliary unit to the refrigeration unit there is provided a removable milk compartment which is generally designated 68 and which is designed to rest upon the top of the cold water reservoir and to receive refrigerated air from the lower ice chamber through one of the screened doors or ports 28.

This milk compartment comprises a rectangular unit having the top and bottom walls 69 and

10 respectively and the side walls 11 and 12. Formed along the bottom wall 10 at the front edge and along the front edges of the side wall 12 and top wall 69 is a flange 13. This flange can serve several purposes. First, the lower part 5 of the flange 13 serves through contact with the front edge of the cold water reservoir, as a stop for the milk compartment when it is inserted into the food chamber to rest upon the top of the cold water reservoir. Second, the side portion 10 of the flange, which is integral with the wall 12, serves to cover the bracket 14, which is provided for the support of one side of a rack or shelf while at the same time also improving the general appearance of the compartment. Third, 15 the top portion of the flange formed along the front edge of the top wall 69 serves to hide the air deflector hood 75 and which is supported upon the top wall 69 by the brackets 16, over the top wall opening 71 which is provided to allow for the free circulation of air through the top of the milk compartment.

The back wall of the milk compartment is generally indicated by the numeral 18, and this is provided with an opening 19 at the proper height 25 to coincide with an air vent 28, when the milk compartment is placed in position at one side of the lower portion of the food chamber.

It will thus be seen that the milk compartment substantially forms a part of the ice unit and by its use the cold air flowing downwardly 30 through the adjacent port 28 can be concentrated within the milk compartment around the bottles which may be placed therein.

If desired the bottom wall 10 may be eliminated or it may be removable so that bottles of milk or other liquids placed within the milk compartment may rest directly upon the top of the cold water reservoir which in effect forms the bottom shelf or floor of the food chamber.

The refrigeration and humidity controlling unit here described is designed to be charged with ice in any form, i. e., either block ice, crushed ice or ice which is shaved and in the form of snow. When used as snow or in finally broken up condition both the upper and lower ice chamber may be filled with ice and it will be readily apparent that the construction is such that a circulation of air will be maintained, the cold air passing downwardly through the lower ice chamber and out of the bottom port while the warm air will rise along the sides of the ice chamber and will enter the upper or top ice chamber by way of the ducts 20 and the openings 19 and 21, being chilled in so flowing, through contact with the outer sides of the walls, 10 and 11. The flow of air circulating through the refrigerator can be controlled by means of the various slides associated with the air apertures and in this way the melting of the ice can be controlled also. Thus by closing the apertures of the ducts 20 and the apertures 36, and also by covering or closing the upper ports 25 of the lower ice chamber, the melting of the ice may be reduced to a minimum, as would be desired if the users of the refrigerator are to be aware.

By the provision of a drawer for the ice, the ice may be easily and quickly drawn out from the refrigerator, or the drawer may be merely pulled out part of the way to permit easy icing of the chamber.

With the arrangement shown and described it will be readily seen also that the entire ice unit or refrigerating unit can be removed from the refrigerator cabinet easily and quickly as the

unit is merely suspended at its sides and back upon the supporting bracket previously referred to.

Where circular refrigerating cabinets are employed the upper and lower ice compartments may be made circular in form and to revolve with revolving shelves, all supported or suspended from the top of the cabinet.

I claim:

1. In a refrigeration structure of the character stated, comprising a cabinet providing a compartment the lower part of which forms a food chamber, a unit designed for installation in the compartment consisting of means disposed above the food chamber part for receiving ice, door means associated with the ice receiving means and facilitating the introduction of ice thereinto, an elongated flat vertically disposed hollow structure located in the food chamber and opening at its upper end into the ice receiving means and having its lower end closed against the escape of ice therefrom and spaced from the bottom of the food chamber and opening therewith, means for receiving and carrying off ice water and condensate from the lower end of said structure and an air port leading from the lower end of such structure into the food chamber.

2. A refrigeration structure as set forth in claim 1, with a separate food storage chamber forming structure in the food chamber and disposed against a wall of said first structure, and means for directing cold air from the lower part of the first structure to said chamber forming structure.

3. A refrigeration structure as set forth in claim 1, in which said ice chamber includes a drawer like unit to which said door is attached, the drawer like unit and the door being constructed and arranged to be drawn out from the ice chamber.

4. A refrigeration structure, comprising a cabinet providing a compartment the lower part of which forms a food chamber, and an ice unit disposed within the cabinet and having an upper ice chamber positioned in the upper part of the compartment and a lower ice chamber extending from the bottom of the upper ice chamber down into the food chamber and terminating in close proximity to the bottom of the food chamber, said lower ice chamber forming a shallow vertical throat which opens at its upper end into the ice chamber and which is open at its lower end, the said lower end of the lower ice chamber having a foraminous covering means thereover, a wall of the lower ice chamber having cold air ports leading from within the lower chamber into the food chamber, means for closing certain of such ports, and a door means closing the entrance to the upper ice chamber.

5. A structure as set forth in claim 4, with means providing an air space around the outer side of the upper ice chamber, and controlled communication means between said space at the top thereof and the top of the interior of the upper ice chamber.

6. In a refrigeration structure, a cabinet providing a compartment the lower part of which forms a food chamber, a refrigeration unit comprising an upper ice chamber disposed in the upper part of said compartment, said ice chamber having side and back walls, lateral flanges extending along the vertical edges of the side walls and along the horizontal edges of the side walls and the back wall and engaging adjacent walls 70 of the compartment to maintain the ice chamber

walls in spaced relation with the compartment walls whereby to provide an air circulation space around the ice chamber, valve controlled ports leading through said ice chamber walls at the top thereof from said air space, door means forming a removable front wall for the ice chamber, means forming an elongated, relatively shallow, lower ice chamber extending downwardly from the lower part of the upper ice chamber and opening therewith, said lower ice chamber at its lower end opening into the food chamber in close proximity to the bottom thereof, means for carrying off melted ice water and condensate from the ice chambers, and cold air ports leading from the lower ice chamber into the food chamber.

7. A structure as set forth in claim 6, including a condensation tray disposed beneath and spaced from the underside of the upper ice chamber, said condensation tray having an inner edge arranged for the discharge of condensate against an adjacent wall of the lower ice compartment to flow down thereover, and being spaced at its sides from adjacent walls of the cabinet for the passage of air between said adjacent walls and the sides of the tray.

8. A structure as set forth in claim 6, with means forming an air duct extending from the lower end of the lower ice chamber to the top of the upper ice chamber, said air duct opening at its lower end into the food chamber and opening at its upper end into the top part of the upper ice chamber.

9. In a refrigeration structure, a cabinet providing a compartment the lower part of which forms a food chamber, door controlled openings leading into the compartment, the cabinet having a sill between said openings, a refrigeration unit comprising an upper ice chamber having bottom, side and back walls, an ice drawer disposed upon said bottom wall and having side walls slidably connected with the first mentioned side walls, a hinged door connected with the bottom of said drawer for vertical opening and closing movement, said door, when in closed position, engaging the forward edges of the first mentioned side walls when the drawer is in the ice chamber, said ice chamber being disposed within the top part of said compartment, means forming an air space around the sides and back of the ice chamber between the latter and adjacent walls of the compartment, means for controlling the flow of air from said air space into the upper part of the ice chamber, a relatively shallow, elongated lower ice chamber disposed vertically in the food chamber and opening at its upper end through the bottom wall of the upper ice chamber, the lower end of the lower ice chamber being open and in close proximity to the bottom of the food chamber, said lower ice chamber having a wall provided with cold air ports leading therefrom into the food chamber, the said upper ice chamber being so disposed in the compartment that when the door of the drawer is closed an air space will be formed between such door and the door for the compartment, and means for controlling the flow of air upwardly from the food chamber to the last mentioned air space.

10. Structure as set forth in claim 9, including a condensation receiving tray supported in spaced relation with and beneath the bottom wall of the upper ice chamber such condensation tray hav-

ing air openings leading upwardly therethrough and further having an upstanding flange at its forward edge in spaced relation with said sill, said flange having air openings formed therethrough, and the condensation tray having an opening at its rear edge through which condensate may be discharged against a wall of the lower ice chamber to flow downwardly over the surface of such wall.

11. An icing and cold air circulating unit for installation into a refrigerator compartment, comprising an ice receiving housing having top, bottom, side and back walls, a shiftable door structure constituting the front wall, a relatively long flat housing extending downwardly from said bottom wall at the back of the first housing, the back wall of the first housing being extended to form the back wall of the flat housing, the lower part of the flat housing having a foraminous closure wall, and cold air venting openings leading from the front of the flat housing.

12. A unit of the character set forth in claim 11, in which said bottom wall slopes downwardly and rearwardly for the discharge of water therefrom into the flat housing.

13. A unit as set forth in claim 11, with a hollow division wall extending upwardly through the flat housing and through the first housing, said division wall being open at its lower end and having vents at its upper end discharging into the upper part of the first housing.

14. A unit as set forth in claim 11, with a sliding floor disposed upon the bottom wall and having upstanding side portions, said sliding floor and side portions being connected with the door carrying the latter whereby the sliding floor, side portions and door provide a shiftable ice carrying drawer.

15. A unit as set forth in claim 11, with laterally projecting positioning flanges extending along the vertical front edges of said side walls and along the top edges of the side walls and the back wall, and valve controlled vent openings formed through the top of the side walls.

16. A unit as set forth in claim 11, with a depending flange secured to the bottom wall across the front edge thereof, a bracket flange secured across the forward side of the flat housing in spaced relation with the underside of the bottom wall, a drip pan formed to position beneath the bottom wall and having an inner down-turned edge portion adapted for engagement upon the bracket flange and an upstanding inwardly turned lip extending across the forward edge of the drip pan for detachable engagement with the first flange.

17. A unit as set forth in claim 11, with a depending flange secured across the bottom wall at the forward edge thereof, a bracket flange secured across the forward side of the flat housing in spaced relation with said bottom wall, a drip pan adapted to position beneath the bottom wall and having a down-turned flange along its inner edge adapted to engage upon the bracket flange, an upstanding in-turned flange formed across the front edge of the drip pan for detachable connection with the first mentioned flange, and side arms forming continuations of the side edges of the drip pan and spaced apart to receive the flat housing therebetween.

CHARLES H. WALBERT.
